UNITED STATES PATENT OFFICE

2,026,300

AIR COMPRESSOR

Lewis J. Clapp, Claremont, N. H., assignor to
 Sullivan Machinery Company, a corporation of
 Massachusetts

Application January 15, 1932, Serial No. 586,843

12 Claims. (Cl. 230—3)

My invention relates to air compressors, and more particularly to portable air compressors. An object of my invention is to provide an improved air compressor. Another object of my invention is to provide an improved portable air compressor having a large potential output. A further object of my invention is to provide an improved portable compressor having an internal combustion engine as the prime mover thereof and having provision for the employment of a plurality of different fuels selectively during operation. A still further object of my invention is to provide an improved portable compressor mechanism having relatively large engine and compressor units, from which substantial amounts of heat have to be dissipated, and having improved cooling arrangements made to care for the dissipation of such heat. Yet another object of my invention is to provide an improved portable compressor having as a part thereof a compound compressor, and having improved cooling means for such a compressor. A still further object of my invention is to provide a large sized portable compressor having improved means for bracing the construction thereof. Other objects and advantages of the invention will appear hereinafter.

In the accompanying drawings, in which I have shown one form which the invention may assume in practice,—

Fig. 1 is a side elevation of the illustrative embodiment of the invention with parts broken away to show details of construction;

Fig. 2 is an approximately central vertical section through the compressor unit;

Fig. 3 is a transverse section through the axes of a single high and low pressure cylinder;

Fig. 4 is a fragmentary view showing a portion of the structure of the compressor, and

Fig. 5 is an axial section through the low pressure cylinder inlet valve mechanism.

Referring to the drawings, it will be observed that front and rear wheels 11 and 12 support a heavy frame 13 at whose forward end a radiator 14 is mounted in vertical transverse planes, and near whose rear end a second radiator 15 is similarly mounted. Adjacent the radiator 14 is an internal combustion driving engine, generally designated 16. This engine is preferably of the type which, while started with gasoline, is normally operated with fuel oil, thereby possessing desirable starting characteristics and yet having marked economy during the regular running of the portable compressor of which it forms a part. This engine is connected through a suit-

able clutch mechanism 17, whose details are not shown but which is manually operable by a lever 18, with a self-aligning semi-permanent type clutch mechanism 19, which is supported on one end of the crank shaft 20 of a compressor 21 (see Fig. 2).

The compressor 21 is of the four-cylinder compound type and comprises two low and two high pressure cylinders. The low pressure cylinders 23 are shown in elevation in Fig. 1, and one is shown in section in Fig. 3. The high pressure cylinders 24 are more clearly shown in Figs. 2 and 3, the former figure showing the cylinders in elevation and the latter showing one of them in section. An intercooler 25 receives compressed air from the low pressure cylinders 23 and supplies it to the high pressure cylinders 24. It will be observed that the intercooler is arranged vertically, primarily in the angular space between the planes respectively including the axes of the low and high pressure compressor cylinders, and is intermediate the radiator 15 and the compressor cylinders.

The low pressure cylinders 23 have a common head 26, and discharge valve mechanisms 27 control the communication between these cylinders and a discharge manifold 28, which is connected by a connection 29 with the intercooler. A connection 30 from the intercooler leads to the inlet manifold 31 of the high pressure cylinders 24. The inlet valves of the low pressure cylinder are designated 32 and have suitable inlet valve opening unloading mechanism 33 associated therewith. Suitable pneumatically operated inlet valve mechanism opening devices 34 are associated with the inlet valves of the high pressure cylinders. At the extreme end of the compressor a receiver 35 is arranged, this being connected by suitable piping 36 with the discharge spaces of the high pressure cylinders 24. Mounted above the receiver 35 is a fuel oil tank 37 connected by suitable supply connections with the fuel supply mechanism of the engine 16. An air pipe 39 leads to a moisture separator 40 and thence through a compressor discharge pressure responsive pilot valve 41, to branch lines 42 and 43; the line 42 leading to the inlet valve unloading mechanisms 33 of the low pressure cylinders, and the line 43 leading to the unloading mechanisms 34 of the high pressure cylinders. The gasoline tank 45 is suitably supported adjacent the engine 16 in the space between the latter and the compressor, and a water supply tank 46 is arranged between the gasoline tank and the com-

pressor and supported on suitable legs 47 by the frame 13. The gasoline from the tank 45 is used in the starting of the engine. When the engine is operating in a normal manner, fuel oil from the tank 37 is the preferred operating medium, and to improve the operation of the engine, appropriate quantities of water from the tank 46 are admitted to the cylinders during the fuel oil operation. The water pump 48 of the engine 16 draws cooling liquid from the radiator 14 through a connection 49 and discharges it through a pipe 50 to the jackets of the engine cylinders, and a connection 51 leads to a return pipe 52 entering the top of the radiator.

15 Referring now to the cooling system of the compressor, it will be observed that a pump 54 suitably driven, as at 55, from the compressor crank shaft, takes cooling liquid from the bottom of the radiator 15 by a pipe connection 56 and discharges it through a connection 57 to the bottom of the intercooler. The water passes from the top of the intercooler through a pipe 58 to a branch connection 59, from which a connection 60 leads to the jackets of the low pressure cylinders, and a connection 61 to the jackets of the high pressure cylinders. Connections 62 and 63 return the water from the tops of the jackets of the low and high pressure cylinders, respectively, to a return connection 64 opening into the top of the radiator 15.

30 A suitable strut 65, herein formed as an extension of the connection 52, opens into a blind pocket 66 in a connector member 67. The connector member 67 has a depending eye 68 formed rigid therewith, and a stud 70 and nuts 71 cooperating with a cap 72 carried by and alined with the pipe 64 rigidly connecting the parts together. It will be noted that by this mode of connection a very strong arrangement is provided; the upright radiator 15, the upright water passages 62 and 63, and the pipe 64 providing a well braced structure, and radiator 14, through the piping 52 and the strut 65 and the connecting devices shown in Fig. 4 and just described, being stoutly connected with the mechanism at the other end of the portable compressor. The low pressure cylinders are provided with an air cleaner protected intake 75.

35 No extended description of the mode of operation of this mechanism is essential, and it may simply be said that the engine 16 is started with the use of gasoline from the tank 45; that when it has been warmed up a transfer is made to fuel oil from the tank 37; that at higher speeds, particularly when fuel oil is being used, water from the tank 46 is admitted to the cylinders of the engine; that the engine is connectable by manipulation of the lever 18, and through the clutch mechanism 17, to drive the compressor 21 when the engine has come up to speed; that the low pressure cylinders of the compressor draw in air through the air cleaner protected intake 75, compress the air and discharge it through the connection 29 into the intercooler; that the high pressure cylinders draw air from the intercooler through the connection 30, compress it and discharge it to the receiver 35 through the piping 36; and that when the receiver pressure reaches a predetermined desired maximum the automatic unloading valve 41 opens to admit air to act upon the inlet valves of the low and high pressure cylinders and open the same, thereby unloading the compressor. When the air pressure falls to the predetermined desired lower pressure limit, the

5 pilot valve 41 vents the air previously supplied to the unloading mechanisms and the compressor again performs its pumping functions. The engine and the compressor are each cooled by their own individual cooling systems. The two radiators spaced by nearly the entire length of the compressor are strongly braced and yet spared a considerable part of the vibration of the engine 16. In the event of minor differences in the length of different compressor frames during 10 manufacture, and in the spacing of the units thereon, the necessary adjustment is provided for by the connecting devices shown in Fig. 4. The gasoline and water tanks are conveniently arranged in well protected position between the 15 engine and the compressor.

While I have in this application specifically described one form which my invention may assume in practice, it will be understood that this form is shown for purposes of illustration and 20 that the invention may be modified and embodied in various other forms without departing from its spirit or the scope of the appended claims.

What I claim as new and desire to secure by Letters Patent is:

25 1. In a compressor mechanism, a frame, a compressor on said frame, an internal combustion driving engine for said compressor also on said frame, said compressor and engine having alined crank shafts, and independent cooling 30- systems for said engine and compressor including radiators individual to each of the same and spaced apart longitudinally of said frame a greater distance than the overall length of the compressor and engine arrangement, to receive 35- the latter between them.

2. In a portable compressor, a frame, alined internal combustion engine and compressor units on said frame, radiators at the remote ends of said units arranged in planes transverse to the 40- alinement of said compressor and engine, and means for effecting circulation of cooling fluid from said radiators to said units.

3. In a compressor mechanism, a frame, a compressor on said frame, an internal combustion driving engine for said compressor also on said frame, and independent cooling systems for said engine and compressor including radiators individual to each of the same, said radiators spaced apart longitudinally of said frame and 50- said compressor and engine disposed wholly within the space between said radiators.

4. In a portable compressor, a frame, an internal combustion engine adjacent one end of said frame, a radiator at the engine end of said 55- frame, a compressor arranged in alinement with said engine and driven thereby, a radiator at the end of the compressor remote from the engine, and means including liquid circulating systems associated with said radiators for bracing the 60- upper ends of the latter.

5. In a portable compressor, a frame, a radiator at one end of said frame, an internal combustion engine adjacent said radiator and having a cooling system of which said radiator forms 65- a part, a compressor operatively connected for drive by said engine and in spaced relation thereto, a radiator remote from said first mentioned radiator, said compressor having a cooling system of which said last mentioned radiator forms 70- a part, and means including circulating piping forming a portion of the cooling system of the compressor for bracing the first mentioned radiator through the bracing means for the second mentioned radiator.

6. In a portable compressor, a frame, a compressor thereon, a multi-fuel driving engine for the compressor, and a plurality of tanks for respectively containing the different fuels of said engine, one arranged between the engine and compressor and the other arranged at the remote end of the compressor from the engine.

7. In a portable compressor, a frame, a compressor thereon, an aligned driving engine for said compressor operative on fuel oil, a fuel oil tank supported by said frame adjacent the end of the latter remote from said engine, and a tank for water to be admitted to the engine during operation of the latter disposed between the engine and the compressor.

8. In a portable compressor, a frame, a compressor on said frame, an aligned engine for driving the compressor also supported on said frame, a plurality of liquid fuel tanks for said engine, one of which is disposed between the engine and the compressor, and a tank for a further liquid used with said engine during operation of the latter with one of said fuels also disposed between said engine and compressor.

9. In a compressor mechanism, a frame, a compressor on said frame, an internal combustion driving engine for said compressor on said frame, a heat exchange device individual to said engine at one end of said frame, and a heat exchange device individual to said compressor at the other end of said frame, said heat exchange devices having said engine and compressor between them on said frame.

10. In a compressor mechanism, a frame, a compressor on said frame, an internal combustion driving engine for said compressor on said

frame, a heat exchange device individual to said engine at one end of said frame, and a heat exchange device individual to said compressor at the other end of said frame, said heat exchange devices having said engine and compressor between them on said frame with said engine and compressor respectively each nearer the heat exchange device which is individual to it.

11. In a compressor mechanism, a frame, a compressor on said frame, an internal combustion driving engine for said compressor on said frame, said engine and compressor having crankshafts whose axes of rotation are each parallel to a line extending longitudinally of the frame, a heat exchange device individual to said engine at one end of said frame, and a heat exchange device individual to said compressor at the other end of said frame, said heat exchange devices having said engine and compressor between them on said frame.

12. In a compressor mechanism, a frame, a compressor on said frame, an internal combustion driving engine for said compressor on said frame, said engine and compressor having crankshafts whose axes of rotation are each parallel to a line extending longitudinally of the frame, a heat exchange device individual to said engine at one end of said frame, and a heat exchange device individual to said compressor at the other end of said frame, said heat exchange devices having said engine and compressor between them on said frame with said engine and compressor respectively each nearer the heat exchange device which is individual to it.

LEWIS J. CLAPP.
